United States Patent Office.

GEORGE MILBANK, OF CHILLICOTHE, MISSOURI.

Letters Patent No. 99,220, dated January 25, 1870; antedated January 14, 1870.

IMPROVEMENT IN STEAM-ENGINE-GOVERNOR CUT-OFFS.

The Schedule referred to in these Letters Patent and making part of the same.

To all whom it may concern:

Be it known that I, GEORGE MILBANK, of Chillicothe, Livingston county, in the State of Missouri, have made certain new and useful Improvements in Governor Cut-Off for Steam-Engines; and I do hereby declare the following to be a full and true description thereof, reference being had to the accompanying drawings, and to the letters of reference marked thereon.

This invention relates to the method of cutting off the steam from the cylinder by a cut-off valve, said valve being controlled by a suitable governor and slotted cam-plate, so that when the speed of the engine is unduly great, the cut-off valve will be moved by the governor to cut off steam earlier, thus giving less steam to the cylinder, and causing a corresponding decrease of power, and reduction of speed.

Said invention relates, also, to the arrangement of the cut-off valve to relieve the same to great extent of steam-pressure, thus permitting a free motion under the impulse of the governor.

To enable those herein skilled to make and use my said improvements, I will now more fully describe the same, referring herein to the accompanying

Figure 1 as a side elevation, to

Figure 2 as a plan, to

Figure 3 as a sectional view of the valve-chest and steam-ports.

In figs. 1 and 2, the steam-chest cover is supposed removed, as also the steam-pipe leading to the steam-chest.

In the usual application of my said invention, I employ ordinary slide-valves, generally as in the figures shown.

A represents the top of the cylinder, with the valve-seats.

a are the steam-ports leading to the front and rear of the steam-cylinder, in the usual manner.

B is the usual slide-valve, moving on the seat A, and arranged with the openings b.

Said valve is operated by the rod B', directly or indirectly connected with the main shaft C, by eccentric collar c.

Ordinarily, I prefer to use the rod D, from said eccentric, operating the lever d, and the rock-shaft E. From said lever d, the connecting-rod D', then transmits motion to the valve-stem B', as required.

In order to regulate the amount of steam passing to the cylinder, as in the nature of this invention, I employ the cut-off valve F, moving steam-tightly upon the upper face of the valve B. Said valve F is usually of such length that it will nearly cover both openings b.

The valve F is operated by the governor G, in the manner now to be described.

From the sliding collar g, which is raised or lowered in accordance with the speed of the engine, owing to the rotating balls g', in the manner usual in the centrifugal governor I, operates the lever H, which is pivoted in the standard h. At its rear end, said lever connects with the link K, upholding the end f of the rod F', which connects, by a suitable jointed stem, to the valve F.

The pin f, of the rod F', moves in a slot, l, of the vibrating cam-plate L, this being connected to the rock-shaft F, above referred to.

A connecting-rod, M, is actuated by an eccentric on the main shaft C, and connects with the cam-plate L, at one of the several holes l, thus causing said plate to vibrate. The revolution of the shaft C, therefore, causes the plate L to move the cut-off valve F, similarly as the valve B is operated. As, however, the pin f of the rod F' is moved in the slot l, by the action of the governor, it is plain, that when the pin f stands high in the slot l, the valve F will follow the movement of the valve B, thus acting generally as a duplicate, but as the pin f drops lower in said slot, the movement of the said valves becomes more dissimilar, and the valve F thus cuts off steam earlier, as required to reduce the speed of the engine.

If the slot l were carried to the horizontal line of the axis of the shaft E, then the pin f, in occupying this position, would transmit no motion to the rod F' and the cut-off valve. If, the valve F then has the length required to cover both openings, in the valve B, steam may be cut off entirely.

The governor G is operated in any manner deemed advisable. In order that it may readily act to move the pin f, as above required, and the valve F, I have arranged to partially balance said valve, by cutting the valve-seat A shorter than the valve B, thus admitting steam under the ends, at a', to the openings b, and relieving the pressure against the cut-off valve for the area of said openings.

Similarly, in the upper surface of the valve B, I arrange the passage b', to enter the steam under the valve F, and thus afford a second reduction of pressure.

In case the governor is not used, a hand-lever may be employed to move the pin f and rod F', and thus the cut-off movement of the valve F is regulated in saw-mill and similar engines.

Having thus fully described my invention,

What I claim, is—

1. The cam-plate L, pivoted at E, and vibrated by the connecting-rod M and an eccentric from the shaft C, when arranged and constructed with the governor G, lever H, link K, and pin f, to operate the cut-off valve F, substantially as set forth.

2. The cut-off valve F, operated through the cam-plate L, by the eccentric on the shaft C, with the main valve B, operated through the lever d, pivoted at the same shaft E, with the cam-plate L, all arranged and constructed substantially as set forth.

3. The valve B, constructed with the passage b' and openings b, and arranged with the valve F and the seat

A, the latter having the curtailed ends a', substantially as set forth.

In witness of said invention, I have hereunto set my hand, in the presence of—

Witnesses: GEO. MILBANK.

GEORGE P. HERTHEL, Jr.

WILLIAM W. HERTHEL.
